UNITED STATES PATENT OFFICE

HARRY E. WEBB, OF TONAWANDA, AND GEORGE F. SEAMES, OF BUFFALO, NEW YORK

DESIGN FOR A STORE BUILDING

Application filed September 15, 1928. Serial No. 28,171. Term of patent 14 years.

To all whom it may concern:

Be it known that we, HARRY E. WEBB and GEORGE F. SEAMES, citizens of the United States of America, residing at Tonawanda and Buffalo, respectively, in the county of Erie and State of New York, have invented a new, original, and ornamental Design for a Store Building, of which the following is a specification, reference being had to the accompanying drawing, forming a part hereof.

The drawing is a perspective view of a store building showing our design.

We claim:

The ornamental design for a store building, as shown.

HARRY E. WEBB. [L. S.]
GEORGE F. SEAMES. [L. S.]
